PRESSURE ATOMIZING LIQUID FUEL
BURNING SYSTEM

Frank W. Ofeldt, Carnot, Pa., assignor to Homestead Valve Manufacturing Company, Coraopolis, Pa., a corporation of Pennsylvania

Application July 2, 1947, Serial No. 758,594

2 Claims. (Cl. 158—36.3)

1

This invention relates generally to pressure atomizing liquid fuel burning systems and more particularly to method and apparatus for smoothing out the pressure pulsations of the atomizing liquid fuel burning system and maintaining the liquid fuel under atomizing pressure to provide a sharp pressure reduction when the flow of fuel is cut off.

This invention may be advantageously employed in the pressure atomizing liquid fuel burning system of a spray generating apparatus employed for cleaning or agricultural purposes. When a spray generating apparatus of this character is employed for cleaning purposes solutions of soap or other similar cleaning compounds are employed to make the spray mixture but when used for agricultural purposes solutions containing a germicide, fungicide, and insecticide are mixed with a conveyor liquid such as water to form solutions. The solution to be employed is fed in metered quantities to a heating zone where it is heated by a pressure atomizing liquid fuel burning system to which fuel is metered in quantities relative to the quantities of solutions fed to the heating zone. The metered quantities of solution and fuel are so proportioned as to generate a vapor or steam pressure and form a spray mixture from the solution which mixture is composed of a liquid and the vapor of a liquid and when discharged to the atmosphere produces an atomized spray for the purpose of cleaning, sterilizing, spraying or other similar purposes for which the spray solution is intended. By properly proportioning the metered quantities of the solution and fuel the spray mixture may be varied to produce a fine atomized spray or a spray of relatively heavy liquid globules which would be considered a wet spray, the former being ideal for agricultural spraying whereas the latter is best suited for cleaning purposes as the force and erosive effect of the water droplets provides a superior cleaning action.

In the pressure atomizing liquid fuel burning systems employed in a spray generating apparatus of this character there is usually an air blower and positive displacement pump of the pulsating flow type for metering the liquid fuel in proportioned quantities correlated with the metered solutions delivered to the heating zone. When the pump and blower is stopped, either by stopping the prime mover or by means of a pressure or temperature control system, the pressure on the liquid fuel slowly decreases and permits the fuel to issue from the burner at pressures

lower than the fuel atomizing pressure and the air from the blower materially decreases and gets out of phase with the amount of fuel delivered. Such a condition causes the fuel to burn slowly creating a considerable amount of soot and smoke. If the fuel pump is stopped this dribbling may produce an accumulation of the fuel within the combustion chamber causing the apparatus to give off soot and smoke when it is again started up. Such an accumulation of fuel within the combustion chamber may find its way to other parts of the apparatus and catch fire causing the spray generator to burn up. Different types of apparatus and different methods have been employed in an endeavor to eliminate this hazardous condition some of which have been partially successful but have not entirely eliminated these difficulties. It was discovered that this problem could be overcome by conducting the liquid fuel under atomizing pressure through a particular type of flexible hose connected between the pump and the atomizing burner. Such a flexible hose may be constructed so as to expand only in a longitudinal direction in order to maintain the liquid fuel under atomizing pressure at the time that the fuel pump is stopped and the action of the flexible hose in contracting longitudinally will forcibly discharge the entire last slug of fuel through the burner at atomizing pressure thereby preventing any dribbling or other low pressure discharge of liquid fuel from the burner.

The principal object of this invention is the provision of method or apparatus for preventing the discharge of liquid fuel from the burner at a pressure lower than atomizing pressure when the fuel supply is stopped.

Another object is the provision of a flexible alleviating conduit in a pressure atomizing liquid fuel system that smooths out pressure impulses and maintains the final discharge of fuel under atomizing pressure when the fuel supply is shut off.

Another object is the provision of a flexible connection between the source of fuel supply and a fuel burner which permits independent manipulation of the burner and also provides an alleviator which smooths out the pressure impulses of the liquid fuel and maintains atomizing pressure on the fuel discharged from the burner when the supply of fuel is shut off.

Another object is the provision of method and apparatus for the final discharge of liquid fuel from a blower type pressure atomizing burner at

atomizing fuel pressure before diminution of the air supply.

Another object is the provision of method and apparatus for the final discharge of liquid fuel from a correlated air fuel atomizing type burner before the air supply is reduced to a position where smoke or soot may be produced.

Other objects and advantages appear herein-after in the following description and claims.

A practical embodiment illustrating the principles of this invention is disclosed in the accompanying drawing wherein:

Fig. 1 is a diagrammatic view of a pressure atomizing liquid fuel burning system comprising this invention.

Fig. 2 is a view partially in section and partially broken away illustrating the flexible connection between the pump and the burner as shown in Fig. 1.

Referring to Fig. 1 of the drawing 1 represents a liquid fuel supply tank or reservoir which may be filled at the top through the opening 2 and is provided with a drain cock 3 at the bottom thereof. The fuel burned in a spray jenny apparatus of the character with which this system is employed, is generally oil. The fuel is withdrawn from the tank 1 through the pipe line 4 to the strainer 5 from thence it passes through the pipe 7 to the inlet chamber 8 of the positive displacement pump 10. The positive displacement pump 10 is provided with the ordinary inlet check valve 11 and the outlet check valve 12 and is provided with a plunger 13 driven by the connecting rod 14 which is pivotally attached at its ends to the plunger 13 and a crank 15 on the rotatably supported pulley 16. A belt drive 17 is arranged to connect the pulley 16 with the pulley 18 on the end of the shaft of the electric motor 20. Although an electric motor is illustrated here as a prime mover any other suitable prime mover such as a gasoline or steam motor may be employed to operate the displacement pump 10.

The displacement pump 10 is also provided with an outlet check valve 21 arranged to permit the fuel to flow through the fixed orifice 22 and through the return pipe line 23 back to the fuel supply tank 1. The orifice 22 thus provides a bypass for the positive displacement pump 10 which not only limits the pressure capable of being developed by the pump but also provides a constant pressure for the fuel discharged from the pump past the outlet check valve 12. The fuel passing the outlet check valve 12 is conveyed through the pipe line 24, the metering valve 6, and the flexible hose connection 25 to the pipe line 26 and the vertically disposed pipe 27, the upper or free end of which has a liquid fuel atomizing burner jet 28 attached thereto. The liquid fuel atomizing burner jet 28 is provided with the deflector 29. A burner of this character is disclosed in United States Letters Patent 2,289,675, issued July 14, 1942.

The flexible hose connection 25 shown in detail in Fig. 2 is made up of a suitable elastomer material such as natural or synthetic rubber or other plastic material having similar characteristics. It is preferable that the material be chosen so that it will resist the action of solvents normally found in fuels such as kerosene, gasoline, fuel oils, or other types of liquid fuels that may be employed for this purpose. The interior wall of the flexible hose as shown at 30 in Fig. 2 is relatively heavy and is made of the elastomer material. This wall is covered with a cross-braided sleeve made of wire or cord such as illustrated at

31. A second layer of the elastomer material is ordinarily formed over the cross-braided sleeve 31 such as illustrated at 32. A second sleeve of similar cross-braided material is placed on the elastomer coating 32 as illustrated at 33 and this latter sleeve 33 is then ordinarily protected by a final covering or coat of the elastomer material as illustrated at 34. The cross-braided cords forming the sleeves 31 and 33 are applied in constructing the flexible hose so that they cross one another at an acute angle less than 90° longitudinally of the axis as shown and is preferably substantially 82°. These cross-braided or basket weave sleeves with the cords crossing at an acute angle permit the flexible hose to have material longitudinal expansion when subjected to an internal fuel pressure, its radial expansion being substantially nil. When the fuel supply to the hose is shut off the whole of the last slug of fuel is quickly discharged. If the braiding is such that internal pressures within the flexible hose will expand readily, it will not function to produce the desired results of maintaining atomizing pressure on the liquid fuel and the last slug of fuel is not forced through the burner quick enough. The flexible hose 25 is preferably constructed in such a manner that it will expand longitudinally instead of the radial expansion common to hose generally. Thus, the hose having predominant expansion longitudinally provides one means for solving the problem of eliminating the dribbling of fuel from the burner when the flow of fuel supply is shut off.

It is preferable to employ permanently attached couplings such as illustrated at 35 on the ends of the flexible hose 25. In practice it has been found that when the fuel system is designed to supply liquid fuel under normal operating pressure of from 175 to 200 pounds per square inch this flexible hose should have an approximate bursting strength of not less than 600 pounds per square inch owing to the shock pressures produced by a pulsating pump. A hose of this character may have an internal diameter of one-fourth of an inch and an external diameter of five-eighths of an inch. It has also been found that the two braided sleeves will properly function when constructed of double-strand cotton cords both of which are embedded within the elastomer material forming the flexible hose.

With a flexible hose of this character, wherein the braids are constructed to allow longitudinal expansion and contraction of the hose when the motor is started or stopped, the fuel will not issue from the burner in an unatomized state because of the sudden longitudinal contraction of the hose which action causes quick discharge of the whole amount of the last slug of liquid fuel and thus eliminates the slow discharge of residual capacity.

The motor 20 is also arranged to drive the blower 36 through the belt connection 37 and the air discharged from the blower passes through the air duct 38 to burner throat 39 from whence it is discharged upwardly around the deflector 29 and mixes with the atomized fuel burner jet 28.

When the prime mover, such as the motor 20, is shut off it rapidly decelerates and the air flow delivered by the blower quickly diminishes to zero. It is then necessary to provide a flexible hose 25 that will produce a final discharge before the air flow from the blower diminishes to a point where soot and smoke is produced. A predominantly radially expanding alleviator hose can't

function to eliminate soot and smoke in this manner.

I claim:

1. In a pressure atomizing liquid fuel burning system, the combination of a source of liquid fuel, a liquid fuel atomizing burner, a positive displacement liquid fuel pump connected to continuously force the liquid fuel from said source through said burner to atomize it for burning, and a flexible hose forming a part of the liquid fuel conduit from the pump to the burner and constructed to expand axially but incapable of expanding radially beyond its normal radial dimension and effect a sharp flow cutoff when the supply of liquid therethrough is stopped.

2. In a pressure atomizing liquid fuel burning system, the combination of a source of liquid fuel, a liquid fuel atomizing burner, a positive displacement liquid fuel pump connected to continuously force the liquid fuel from said source through said burner to atomize it for burning, a blower connected to supply air to the atomized fuel, motor means to operate the fuel pump and blower which are adjusted to correlate the supply of fuel and air for proper combustion, and a portion of the liquid fuel conduit from the pump to the burner being a flexible hose constructed to expand longitudinally but incapable of expanding radially beyond its normal radial dimension when sub-

jected to atomizing fuel pressure and to quickly recover its original shape without further deformation to produce a single final discharge of atomized fuel from the burner before the air supply diminishes to a point where soot and smoke is produced when the motor means is stopped.
